RAILWAY SIGNALING APPARATUS

David C. Bettison, Omaha, Nebr.

Application August 20, 1935, Serial No. 37,024

20 Claims. (Cl. 246—41)

My invention relates to railway signaling apparatus of the type involving track circuits, and has for an object the provision, in apparatus of this type, of a track circuit having a shunting sensitivity which is independent of variations in ballast resistance. More particularly, my invention relates to a track relay system which is unaffected by a steady value of track current supplied thereto, above a given predetermined minimum value, or to gradual changes in this current, but which will respond positively to a rapid change in the track current received by the relay system, such for example as occurs when a train enters the track circuit.

I will describe three forms of apparatus embodying my invention, and will then point out the novel features thereof in claims.

The present application is a continuation in part of my copending application Serial No. 713,400, filed March 31, 1934, for Railway signaling apparatus, in so far as the subject matter common to the two cases is concerned.

In the accompanying drawings, Fig. 1 is a diagrammatic view showing one form of apparatus embodying my invention. Fig. 2 is a diagrammatic view showing a modified form of a portion of the apparatus illustrated in Fig. 1. Fig. 3 is a diagrammatic view which shows a further modification of the apparatus illustrated in Fig. 1 and also embodying my invention.

Similar reference characters refer to similar parts in each of the views.

Referring to Fig. 1, the reference characters 1 and 1^a designate the track rails of a stretch of railway track along which traffic normally moves in the direction indicated by the arrow. These rails are divided by insulated joints 2 to form a track section D—E. Section D—E is provided with a track circuit comprising a battery H and a resistor R connected across the rails at the exit end of the section, as well as the winding of armature A of a relay G connected across the rails at the entering end of the section.

Relay G is a galvanometer type relay comprising a field F, which may be either a permanent magnet or an electromagnet, and a movable armature A which carries the track winding W and which is arranged to rotate about a shaft P, in the field set up by the pole pieces of the magnet F. A cylindrical soft iron core C may be used to provide uniform flux distribution in the armature air gap, in well known manner. One terminal of the armature winding W is connected with rail 1 by means of wire 3, and the other terminal is connected with rail 1^a by means of wire 4. A ten-

sion spring S provides the restraining force against which the armature torque is developed when current flows in winding W. The terminals of winding W are so connected with the respective track rails that current from battery H will cause the armature A to rotate in the counterclockwise direction as viewed in the drawings, whereby the armature will assume a position such as that illustrated.

Fastened to the armature and insulated therefrom is a rigid or fixed contact member 5, to which is attached at its lower end a flexible or spring member 6 which carries at its upper end a gear segment 1. The spring member 6 carries a flexible contact spring 8 fastened thereto and insulated therefrom, which normally makes electrical contact with the fixed contact member 5. The gear segment 1 cooperates with a pinion 17 mounted on a shaft which carries a vane or disc 9, the purpose of which will be explained hereinbelow.

Contact 8—5 controls the energizing circuit for a relay T which may be used to control, over its contacts 13—18 and 13—19, any suitable apparatus commonly controlled by the usual track relay, such for example as lamps G and R of the signal L, which are energized from a source of current having the terminals B—C, over the wires 20 and 21, respectively. The circuit for relay T may be traced from one terminal of the battery B, wire 10, contact 8—5, wire 11, winding of relay T, and wire 12, to the other terminal of the battery.

The spring member 6 is sufficiently flexible to permit members 5 and 6 to separate readily upon the occurrence of a quick clockwise movement of armature A, the static inertia of vane 9 acting to prevent instantaneous follow of segment 1 and member 6. If greater damping is desired, over that resulting from the inertia of vane 9 and bearing and gear tooth friction, the vane 9 can be made of non-magnetizable conducting material such as aluminum or copper, and made to rotate in the field of a strong permanent magnet such as M, whereby increased damping will be available due to the eddy current effect in the vane.

The contact spring 8 is designed to have an appreciable amount of compression or follow, so that the rigid contact member 5 may move through an appreciable arc (when the current in winding W decreases suddenly) before contact 8—5 opens. The stop pin 15 limits the maximum counterclockwise movement of segment 1, and the stop pin 16 acts to open contact 8—5, should the track current fall below a value which is established as a

minimum at which the track circuit can be safely operated in wet weather.

In describing the operation of the apparatus as a whole, I shall assume that with the apparatus in the normal condition as illustrated, a train enters section D—E. The shunt afforded by the wheels and axles of the train will suddenly reduce the amount of current flowing in winding W, whereupon armature A and contact member 5 will quickly rotate in the clockwise direction due to the restoring force of the spring S. The amount of rotation will depend upon the effectiveness of the train shunt. Due to the inertia of vane 9, spring member 6 will not follow the quick movement of member 5, so that contact 8—5 will open, releasing relay T, thus closing back contact 13—19 which causes lamp R of signal L to become energized. As soon as armature 13 of relay T drops, the brake pad 14 will engage the periphery of vane 9, to prevent further movement of the vane as well as of member 6, until such time as the train leaves the section and contact 8—5 becomes closed to reenergize relay T.

When the train leaves section D—E, there will be an increase in the current through winding W, and this change will cause armature A and member 5 to rotate in the counter-clockwise direction, closing contact 8—5, and restoring the apparatus to its normal condition.

It will be apparent from the foregoing that the opening of contact 8—5 of relay G, and therefore the release of relay T, is independent of the track energy level and is dependent only on a quick change in the amount of current supplied to winding W, this change being of a relatively small value and constant for any energy level. Therefore, changes in the characteristics of the track circuit due to variations in ballast resistance, track battery voltage, or other conditions, will not affect the operation of the system. To make the operation more clear, let it be assumed, for example, that winding W has a resistance of 4 ohms and is receiving a current of 150 milliamperes with the track unoccupied and ballast dry. The follow or compression of spring 6 may be so adjusted that a change of 30 milliamperes is required to open contact 8—5. If the current in winding W drops to 100 milliamperes when a train enters the section, then contact 8—5 will open when this current has decreased to 120 milliamperes, and relay T will release to keep segment 7 and member 6 fixed in position thereafter. When the train leaves the section, contact 8—5 will re-close as soon as the current has increased to 120 milliamperes, picking up relay T and disengaging the brake from the vane, so that any further increase in current results in compression of contact 8—5, and movement of segment 7 to the left.

As explained in the above example, any shunt which is sufficient to reduce the current in winding W by 30 milliamperes will cause a release of relay T, irrespective of the initial track energy level. On the other hand, a track circuit of the usual type, employing a 4 ohm track relay energized with 150 milliamperes of current during dry weather requires a train shunt of sufficiently low resistance to reduce the relay current from 150 to approximately 40 milliamperes, depending on the relay design. That is, the train shunt must be low enough to by-pass 110 milliamperes, instead of 30 as in the illustration given above. The increased shunting sensitivity of the apparatus embodying my invention is therefore self-evident.

Since ordinary changes in ballast resistance

and track battery voltage occur slowly, contact 8—5 will remain closed during any movement of armature A resulting from such changes.

Referring now to Fig. 2, I have shown one manner in which the apparatus embodying my invention may be applied to an alternating current track circuit. The rails of section D¹—E¹ are supplied with alternating current from a source BX—CX, through a track transformer TR and a current-limiting reactor X. At the relay end 5 of the track circuit, a rectifier K is interposed between the rails and the track winding W of relay G, for the purpose of converting the alternating rail current into unidirectional current for operating the relay G. The operation of the system from this point on is the same as previously described, and will be clear without further explanation.

It is to be noted that the design of the relay G may be varied in numerous ways, while at the same time accomplishing the essential purposes of my invention. For example, it is not essential that the soft iron core C be used. Furthermore, the coil W may be wound on a movable soft iron armature, for increasing the armature torque. Also, other means than the spring S may be used for biasing the armature A to the deenergized position. Similarly, it is contemplated that quick movement of member 6 may be retarded in numerous other suitable ways, as for example by a dashpot arrangement operated by member 6, and locked against subsequent movement by the release of armature 13 of relay T.

Although relay T has been shown as a slow pickup relay, it will be understood that the slow pickup feature, while helpful, is not essential for the proper operation of the system. Also, if desired, the flexible member 6 may be provided with an insulated hook which engages the rigid member 5 to prevent further clockwise movement of armature A, thus establishing a maximum permissible opening for contact 8—5 to make it unnecessary for member 5 to move through more than a small arc before contact 8—5 is closed, upon the exit of a train from the section.

Furthermore, the geared vane 9 may be dispensed with by attaching a magnetic drag vane, or other inertia apparatus, directly to the free end of flexible member 6.

Referring to Fig. 3, the apparatus of this figure accomplishes substantially the same results as the apparatus of Fig. 1, but makes use of a tractive type relay TR in place of the galvanometer relay G. Track relay TR is so designed that armature A will occupy a position corresponding to the amount of energy received by winding W from the track. For example, when the track ballast is dry, the armature A will be in its high position close to the pole face of magnet L, whereas when the track ballast is wet, armature A will be in its low position. For ballast conditions in between these two extremes, armature A will occupy an intermediate position. The particular air gap design for accomplishing this result may vary considerably. For example, armature A may be of the plunger type or of the Z-armature type, or of any other suitable design. The restraining force for armature A may be provided by a suitable weight or by a spring such as the spring S shown in the drawings.

Armature A carries a contact finger 22 which cooperates with a contact disc 23 attached to shaft 31 of a dashpot P. If the movement of armature A is slow, such as that resulting from a change in ballast conditions, disc 23 will follow

the movement of finger 22 and the contact 22-23 will remain closed. If, however, a train enters the section, armature A will drop quickly and contact 22-23 will open, thus deenergizing the 5 brake relay BR and also the signal control relay T. The circuit for relays BR and T includes battery B, wires 26 and 27, contact 23-22, and wires 28 and 29. When the armature of relay BR drops, finger 30 causes the brake 24, which is 10 pivoted at 25, to press against the shaft 21 of the dashpot, thus preventing a change in the position of disc 23 until relay TR picks up following the exit of the train from the section.

It will be apparent from the foregoing description that the apparatus of Fig. 3 provides the same type of operation as provided by the apparatus of Fig. 1, and it is believed that the complete operation of this apparatus will be clear without further explanation from a comparison 15 with Fig. 1.

It is not essential, of course, that a dashpot be used, as any movable member so designed that it can be moved slowly without undue resistance but in which a rapid movement is restrained, can 20 be used to cooperate with the disc 23 and finger 22.

Although I have herein shown and described only three forms of apparatus embodying my invention, it is understood that various changes and modifications may be made therein within the 25 scope of the appended claims without departing from the spirit and scope of my invention.

Having thus described my invention, what I claim is:

1. In combination, a section of railway track, a 30 source of current connected across the rails of said section, a control relay, a circuit including a normally closed contact for energizing said relay, means receiving energy from said rails for controlling said contact in such manner that said 35 contact will open upon a sudden decrease in the energy received by said means but that said contact will remain closed when the energy change occurs slowly, means governed by said relay effective when said contact opens and said 40 relay becomes deenergized for preventing the contact from reclosing until a predetermined increase in the energy received by said means occurs, and signaling apparatus governed by said 45 control relay.

2. In combination, a section of railway track, a 50 source of current connected across the rails of said section, a first relay receiving energy from said rails having a movable armature which assumes different positions in accordance with the 55 amount of energy received by said relay, a contact operated by said armature and comprising a rigid member and a flexible member normally in contact with each other, inertia means operated by said flexible member for causing said 60 contact to open upon a quick movement of said armature but to remain closed when the movement of said armature is gradual, a second relay controlled by said contact, means controlled by said second relay for at times preventing operation 65 of said flexible member by said armature, and signaling apparatus governed by said second relay.

3. In combination, a section of railway track, a 70 source of current connected across the rails of said section, a galvanometer relay receiving energy from said rails and having a movable member which assumes different positions in accordance with the amount of energy received by said relay, a contact having inertia means associated therewith and operated by said movable 75

member in such manner that said contact will remain closed when the movement of said member is gradual but will open upon a sudden movement of said member resulting from the entry of a train into said section, and signaling apparatus controlled by said contact. 5

4. In combination, a section of railway track, a source of current for said section, means receiving energy from said rails and movable to different positions determined in accordance with 10 the amount of energy received from said rails, a normally closed contact operated by said means and comprising a rigid and a flexible member which move as a unit when the movement of said means is gradual, a damping vane operated by the flexible member of said contact for causing said contact to open upon a quick movement of said means, and signaling apparatus controlled 15 by said contact.

5. In combination, a section of railway track, a 20 source of current connected across the rails of said section, a control relay, a circuit including a normally closed contact for energizing said relay, means receiving energy from said rails for controlling said contact in such manner that said 25 contact will open upon a sudden decrease in the energy received by said means but that said contact will remain closed when the energy change occurs slowly, and means governed by said relay for preventing said contact from reclosing until 30 the energy received by said means reaches a level determined by the energy level existing at the time said contact initially opens.

6. In combination with a section of railway track provided with a track circuit including a 35 source of energy, a winding receiving energy from said track circuit, a first contact member biased to one position and urged against such bias by the force of said winding, a second contact member normally occupying a given relation with 40 respect to said first contact member, and means including a dashpot effective during a rapid but not during a gradual change in the force applied to said first member for changing the relation of 45 said two contact members.

7. In combination with a section of railway track provided with a track circuit including a source of energy, a track relay receiving energy from said track circuit and having an armature which adjusts its position in accordance with 50 the amount of energy received by the relay, a first contact member biased to one position and urged by the force of said armature against said bias, a second contact member normally occupying a given relation with respect to said first contact member, and means effective during a rapid but not during a gradual change in the position of 55 said armature for changing the relation of said two contact members.

8. In combination with a section of railway 60 track provided with a track circuit including a source of energy, a track relay receiving energy from said track circuit and having a core and an armature separated by an air gap the length of which varies in accordance with the amount of 65 energy received by said relay, a first contact member biased to one position and urged by the force of said armature against said bias, a second contact member normally occupying a given relation with respect to said first contact member, and 70 means effective during a rapid but not during a gradual change in the length of said air gap for changing the relation of said two contact members.

9. In combination with a section of railway 75

- track provided with a track circuit including a source of energy, a winding receiving energy from said track circuit, a first contact member biased to one position and urged against such bias by the force of said winding, a second contact member normally occupying a given relation with respect to said first contact member, means effective during a rapid but not during a gradual decrease in the force applied to said first member for changing the relation of said two contact members, and means controlled by said two contact members effective when said given relation between them is changed for fixing the position of said second contact member.
15. 10. In combination with a section of railway track provided with a track circuit including a source of energy, a winding receiving energy from said track circuit, a first contact member biased to one position and urged against such bias by the force of said winding, a second contact member normally engaging said first contact member, means effective during a rapid but not during a gradual decrease in the force applied to said first member for separating said two contact members, and means controlled by said two contact members effective upon the separation thereof for fixing the position of said second contact member until such time as said first contact member engages said second contact member.
15. 11. In combination with a section of railway track provided with a track circuit including a source of energy, a winding receiving energy from said track circuit, a first contact member biased to one position and urged against such bias by the force of said winding, a second contact member normally occupying a given relation with respect to said first contact member, and a retarding mechanism operatively connected with said second contact member, whereby the relation between said two contact members will be changed during a rapid but not during a gradual change in the force applied to said first contact member.
15. 12. A galvanometer relay for railway signaling track circuits comprising, in combination, a movable coil adapted to be energized from the track and occupying progressively different positions in accordance with the amount of energy received from the track, a normally closed contact operated by said movable coil, and means for causing said contact to open upon a relatively quick change in said energy but to remain closed when the change in energy received by said movable coil is gradual, whereby said relay is capable of distinguishing between the presence of a train shunt and changes in ballast resistance of said track.
15. 13. A galvanometer relay for railway signaling track circuits comprising, in combination, a movable coil adapted to be energized from the track and occupying progressively different positions in accordance with the amount of energy received from the track, a first contact member biased to one position and urged against such bias by the force applied thereto by said movable coil, a second contact member normally engaging said first contact member, and means effective during a rapid but not during a gradual change in the force applied to said first member for separating said two contact members.
15. 14. A relay for railway signaling track circuits comprising, in combination, a movable element adapted to be energized from the track and occupying different positions in accordance with the amount of energy received from the track, a first contact member biased to one position and urged against such bias by the force applied thereto by said movable element, a second contact member normally occupying a given relation with respect to said first contact member, means effective during a rapid but not during a gradual change in the force applied to said first member for changing the relation of said two contact members, and means controlled by said two contact members effective when said given relation between them is changed for fixing the position of one of said contact members.
15. 15. In combination with a section of railway track and a source of current connected across the rails of said section, a track relay energized from the rails of said section, an armature for said track relay comprising a movable element which occupies progressively different positions in accordance with the amount of energy received from the track by said track relay, and means effective during a rapid change in the energy received by said track relay such as occurs when a train enters the section but not during a gradual change resulting from a variation in ballast resistance for preventing movement of said movable element until the train vacates said section.
15. 16. In combination with a section of railway track and a source of current connected across the rails of said section, a track relay energized from the rails of said section over a circuit of substantially constant resistance between the rails and said track relay, means for causing the armature of said relay to respond differently to a sudden change such as occurs when a train enters the section and a gradual change such as occurs due to ballast resistance variation, and means effective upon said sudden change for fixing the pickup point of said armature in accordance with the track relay energization existing just prior to said sudden change.
15. 17. In combination with a section of railway track and a source of current connected across the rails of said section, a track relay energized from the rails of said section over a circuit of substantially constant resistance between the rails and said track relay, a contact for said track relay, means effective upon a sudden change but not upon a gradual change in the energy received by said track relay for operating said contact, and means effective following said sudden change for maintaining said contact in its operated condition by constraining the mechanical movement thereof.
15. 18. In combination with a section of railway track and a source of current connected across the rails of said section, a galvanometer track relay energized from the rails of said section over a circuit of substantially constant resistance between the rails and said track relay, a movable coil for said track relay occupying progressively different positions in accordance with the amount of energy received from the rails by said track relay, a normally closed contact operated by said movable coil, and means effective upon a sudden change in said energy for causing opening of said contact.
15. 19. In combination, a section of railway track, a source of current connected across the rails of said section, a control relay, an energizing circuit for said control relay, a normally closed contact included in said circuit, retarding means associated with said contact, a winding receiving energy from said rails for controlling said contact in cooperation with said retarding means

in such manner that said contact will open when and only when a sudden predetermined decrease in the energy received by said winding occurs but that said contact will remain closed when the energy change occurs slowly, and signaling apparatus governed by said control relay.

20. In combination, a section of railway track, a source of current connected across the rails of said section, an auxiliary relay receiving energy from said rails and having a normally closed contact which opens on a predetermined small decrease in the energy received by said

auxiliary relay when a train enters said section, a control relay, an energizing circuit for said control relay governed by said contact, means governed by said control relay for determining the amount of energy at which said auxiliary relay will reclose said contact upon the exit of the train in accordance with the magnitude of the ballast resistance of said track section, and signaling apparatus governed by said control relay.
